UNITED STATES PATENT OFFICE

155,485

DESIGN FOR A CLOTHESLINE PULLEY ASSEMBLY

John W. Conway, Bridgeport, Conn.

Application May 21, 1947, Serial No. 139,188

Term of patent 7 years

(Cl. D49—1)

To all whom it may concern:

Be it known that I, John W. Conway, a citizen of the United States, residing at Bridgeport, county of Fairfield, State of Connecticut, have invented a new, original, and ornamental Design for Clothesline Pulley Assembly, of which the following is a specification, reference being had to the accompanying drawing forming a part thereof.

Fig. 1 is a perspective view of a clothesline pulley assembly, showing my new design, and

Fig. 2 is a side view thereof.

I claim:

The ornamental design for a clothesline pulley assembly, substantially as shown.

JOHN W. CONWAY.
